UNITED STATES PATENT OFFICE

90,831

DESIGN FOR A DISPLAY STAND OR THE LIKE

William K. Battersby, Providence, R. I.

Application July 25, 1933. Serial No. 48,823

Term of patent 7 years

To all whom it may concern:

Be it known that I, WILLIAM K. BATTERSBY, a citizen of the United States, residing at 190 Laban Street, in the city of Providence, county of Providence, and State of Rhode Island, have invented a new, original, and ornamental Design for a Display Stand or the like, of which the following is a specification, reference being had to the accompanying drawing, forming a part thereof, in which:

Fig. 1 is an elevational view of the display stand; and

Fig. 2 is a plan view of the same.

I claim:—

The ornamental design for a display stand or the like substantially as shown.

WILLIAM K. BATTERSBY.
